CLAIM

The ornamental design for a wine case, as shown and described.

DESCRIPTION

FIG. 1 is a perspective view of a wine case showing my new design, the case having been rotated to its side and the lid having been removed for convenience of illustration;

FIG. 2 is a front perspective view thereof;

FIG. 3 is a top plan view thereof;

FIG. 4 is a front elevational view thereof, the rear view being a mirror image;

FIG. 5 is a right side elevational view thereof, the left side being a mirror image; and,

FIG. 6 is a bottom plan view thereof.

FIGS. 3-6 have been shown on an enlarged scale with respect to FIGS. 1 and 2.

FIG. 1

FIG. 2

FIG. 4
